UNITED STATES PATENT OFFICE

2,547,641

BATH CABINET FOR BABIES

Walter L. Henderson, Marshall, Minn.

Application October 12, 1945, Serial No. 621,976

1 Claim. (Cl. 312—201)

1
The present invention relates to new and useful improvements in apparatus for use in bathing babies and more particularly to the provision of a chest of drawers in which the baby's clothing and other equipment may be stored together with a foldable table supported at one side of the chest of drawers and on which the baby may be supported while being bathed.

An important object of the present invention is to provide means for swingably mounting certain of the drawers to provide access thereto and arranging the drawers whereby the same may all be maintained in open position to afford access to the contents thereof.

A still further object of the invention is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a perspective view of my improved cabinet with the drawers extended.

Figure 2 is a top plan view.

Figure 3 is a front elevational view showing the drawers in closed position, and with the table in extended unfolded position.

Figure 4 is a side elevational view.

Figure 5 is a fragmentary view in elevation showing the support for the inner edge of the table.

Figure 6 is a fragmentary top plan view showing the table in folded position.

Figure 7 is a vertical sectional view of the wash basin holder.

Figure 8 is a detail for the hinged connection for the inner end of the table.

Figures 9 and 10 are perspective views of the releasable supporting bracket for the inner end of the table.

Figure 11 is a fragmentary elevational view of the hinged end of the table.

Referring now to the drawings in detail wherein for the purpose of illustration I have disclosed a preferred embodiment of the invention, the numeral 5 designates a chest generally and which includes a pair of rear legs 6 which extend throughout the height of the chest and to which the rear edges of an upper stationary tray 7 and a lower stationary tray 8 are secured both

trays being of box-like form. The front edge of the lower stationary tray 8 is supported on a pair of front legs 9.

An upper intermediate drawer 10 and a lower intermediate drawer 11 are positioned between the drawers 7 and 8, the drawer 10 being hinged as at 12 at one rear corner to one of the rear legs 6 while the drawer 11 is likewise hinged as at 13 to an opposite rear corner to the other of the legs 6 whereby the drawers 10 and 11 may swing horizontally toward opposite sides of the chest into an open position as indicated in Figure 1 of the drawings, to expose the contents of the lower stationary tray 8 as well as the intermediate drawers 10 and 11.

The upper stationary tray 7 is provided with a stationary top 14 at the rear portion thereof and to the front edge of which is hinged a cover 15 for vertical swinging movement to thereby afford access to the contents of the upper tray 7. The hinged cover 15 is adapted to fold rearwardly upon the stationary top 14 as indicated by the dotted lines in Figure 4 of the drawings.

A table or shelf 16 has one corner hinged as at 17 to one side of the upper tray 7 adjacent its rear edge for downward swinging movement of the table. To the underside of the table 16 adjacent its other inner corner is secured a bracket 18 in which a catch 19 is slidably mounted and having a downturned tongue 20 at its inner end adapted for engagement in a keeper socket 21 secured to the adjacent side of the tray 7 whereby to support the front edge of the table in its raised position.

To the underside of the front outer corner of the table 16 is secured an extensible sectional leg 22 adapted for folding against the underside of the table and when in its open position and adapted for supporting the front edge of the table in a horizontal position substantially in the plane of the top of the chest. The leg 22 may be secured in vertically adjusted position by means of the bolts and wing nuts 23 connecting the sections of the leg to each other.

To the front of the upper stationary tray 7 is secured a horizontal U-shaped bracket 24 and in which is pivotally mounted a vertical pin 25 on the inner end of a horizontal arm 26 and to the outer end of which is suitably secured a ring 27 for engaging under the flange 28 of a wash basin 29 to support the basin for horizontal swinging movement.

To the side of the upper tray 7 opposite from the table 16 is secured a conventional form of towel rack 30.

When the device is not in use the hinged lid 15 is closed, the drawers 10 and 11 are swung inwardly into the position as shown in Figure 3, the leg 22 folded upwardly against the underside of the table 16 and the table swung downwardly at its front edge. The trays 7, 8 and drawers 10, 11 are then arranged in superposed relation, one closing the other.

When the device is placed in use the table 16 is swung upwardly and supported at its front edge by the folding leg 22 and a baby may then be bathed on the table. The drawers 10 and 11 are swung toward opposite sides as shown in Figure 1 into their open position and which also uncovers the lower stationary tray 8. The upper drawer 10 may be swung under the table 16 into open extended out-of-the-way position but spaced below said table for quick access to the top thereof by a person bathing a baby on the table.

Any suitable latch means may be provided for securing the drawers in a closed position if desired.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully compre-

hended by the spirit of the invention as herein described and the scope of the appended claim.

What is claimed is:

5 A bath cabinet for a baby comprising a chest including a stationary tray having a top adapted to be opened and closed, a table extending from one side of the tray flush with the top when said top is closed to form an extension of said top for bathing a baby thereon, and a drawer in said chest beneath said tray closed by the tray and pivotally mounted for horizontal swinging out of said chest under said table, said tray spacing the drawer when swung under the table below said table for access to the top of the drawer by a person bathing a baby on the table.

10 15 WALTER L. HENDERSON.
